UNITED STATES PATENT OFFICE.

CHARLES L. RAYFIELD, OF CHICAGO, ILLINOIS, ASSIGNOR TO BENEKE MANUFACTURING COMPANY, OF CHICAGO, ILLINOIS, A CORPORATION OF ILLINOIS.

CARBURETOR.

Application filed November 3, 1919. Serial No. 335,360.

This invention relates to a type of carburetors known as overflow carburetors, wherein the float chamber is supplied with fuel from an auxiliary chamber which first fills with fuel and then overflows into the float chamber and, when the float within the float chamber rises to a predetermined level operates to cut off the inlet to the overflow chamber. The invention also comprehends an improved arrangement of priming passages for starting motor to which the carburetor is attached, as well as a novel compensating means of supplying fuel from different sources into the carbureting chamber to properly carburete the air for various conditions of operation so that a proper fuel mixture is supplied to the engine under all conditions of operation and yet with the carburetor so constructed as to minimize moving parts.

It is therefore an object of this invention to provide a simple type of tube carburetor with a minimum of moving parts and provided with fuel supply means operating according to conditions of operation of the engine to compensate for the different quantities of air drawn through the carburetor to supply a properly carbureted mixture to the engine for all conditions of operation thereof.

It is also an object of this invention to supply a side outlet carburetor having a plurality of fuel nozzles and with an overflow chamber supplying fuel to the float chamber with one of the fuel jets supplied directly from the overflow chamber and another supplied both from the overflow and float chamber, and arranged with a system of air and fuel passages to properly compensate in the supply of fuel, for the different quantities of air drawn through the carburetor to supply a properly carbureted mixture to the engine at all times.

Other and further important objects of this invention will be apparent from the disclosures in the drawings and specification.

The invention (in a preferred form) is illustrated in the drawings and hereinafter more fully described.

Drawings.

Figure 1 is a top plan view of a carburetor embodying the principles of my invention.

Figure 2 is a sectional detail with parts omitted taken on line 2—2 of Figure 1.

Figure 3 is a vertical section taken through the carburetor on line 3—3 of Figure 1 with parts omitted and parts shown in elevation.

Figure 4 is a horizontal section taken through the carburetor substantially upon line 4—4 of Figure 3.

Figure 5 is a sectional view taken substantially on line 5—5 of Figure 4 with parts omitted and parts shown in elevation.

Figure 6 is a side elevation of the carburetor with parts broken away and parts shown in section to illustrate the construction.

Figure 7 is a fragmentary enlarged section on the line 7—7 of Figure 5 showing a detail of the throttle shaft.

Description.

The upper portion of the carburetor is cast as a unit comprising a casing denoted by the reference numeral 1 and is attached upon a casing section 2 with an overflow chamber 3, formed thereon and attached therebeneath is a third casing section affording a float chamber 4 having a lateral extension 5 which extends beneath the overflow chamber 3. The chamber in the casing 1 which affords the mixing chamber and outlet of the carburetor as shown clearly in Figure 4, is provided with an inserted Venturi tube 6 secured therein and an attaching flange 7 surrounds the outlet opening of the carburetor. Pivotaly mounted within said casing 1 is a throttle valve 8, mounted upon a vertical operating shaft 9. At the opposite end of the casing section 1, an air inlet opening is provided, controlled by a choker valve 10 mounted on the vertical shaft 11. The shaft 11 is extended downwardly through a boss 11^a on the cover of the float chamber, is cored axially with the passage 11^b, and has a transverse port 11^c. The transverse port 11^c registers with a port 11^d in the boss 11^a when the choke valve is closed, to admit air into the float chamber. The inlet of fuel for the carburetor is through a fitting 12 communicating into the upper end of the overflow chamber 3 by means of a passage 13 past an upwardly directed needle valve 14 having a stem 15 of triangular section. A passaged seat mem-

ber 16 is threaded into an extension formed in the upper end of the overflow chamber 3 communicating with the passage 13 to form a seat for the needle valve closure 14.

5 The stem 15 of the needle valve is slidably mounted in an upright overflow tube or standpipe 17 threaded into the floor of said overflow chamber 3 and secured on the stem 15 near the upper end thereof, is a hood or cap 18 having apertures 19 therein. Said hood is normally spaced above the upper end of the standpipe 17 so that fuel entering past the needle valve 14 is spilled over said hood into the chamber 3 and as the level 10 therein rises, the fuel flows upwardly beneath the hood 18 and over the top of the standpipe 17 for discharge therethrough into the float chamber 4. The apertures 19 prevent the forming of a seal which would cause 15 siphoning of the fuel from the overflow chamber 3 into the float chamber 4. The lower end of the stem 15 rests upon a pivoted lever 20, the free end of which is of yoke shape and rests upon the upper surface of a 20 float 21 disposed in the float chamber 4. A chamber 22 is formed within the casing section 2 as shown in Figure 3 and threaded into the casing section is an apertured plug member 23, affording a closure for the lower 25 end of said chamber. Inserted through an aperture in the bottom of the float chamber 4 is a tube 24 threaded into said plug member 23 and having a nut 25 secured on the outer, lower end thereof in sealing relation 30 with the wall of the float chamber 4, and provided with lateral apertures 26 at its upper end and apertures 27 at its lower end. A conical screen 28 is held clamped around the lower end of the tube 24 enclosing the 35 apertures 27. A plug member 29, having an upwardly projecting tubular extension is secured into the casing section 2 forming a closure for the upper end of the compartment or chamber 22 and inserted through 40 said plug member and extending upwardly and into the Venturi tube 6 in the casing section 1, is a tube 30 spaced from and extending downwardly in sealing relation through the plug member 23. Said tube 30 45 is provided with fuel outlet apertures 31 near the upper end thereof and with apertures 32 communicating with the interior of the tube 24 at the upper end of the float chamber 4. Said tube also extends downwardly into the 50 tube 24 from which it is spaced, to a point slightly above the apertures 27. As shown clearly in Figure 3 the upper end of the member 29 is swaged inwardly into sealing relation with the tip of the tube affording an annular passage therearound which communicates into the chamber 22.

An air inlet passage 33 is provided for the float chamber 4 in an extension of the casing section 2 as shown in Figure 3 and is controlled by a manually adjustable needle valve 34 which is locked in adjusted position by a nut 35. Cored within the casing 2 is a passage 36 communicating with the chamber 22 as shown in Figures 2 and 4, leading beneath an outlet passage 37 in a valve seat member 38 forming an outlet from the overflow chamber 3. Threaded into the upper end of the overflow chamber 3 is a plug element 39 having a passage therethrough and threaded to receive an adjustable needle valve 40 to control the flow through said passage 37 and a spring impelled ball detent 41 is provided in said element 39 to bear against the needle valve 40 to hold the same in adjusted position. Engaged around the lower end of the element 39 and also around the passaged seat member 38 is a cylindrical screen 42 so that fluid leaving the overflow chamber 3 by way of the passage 37 and passage 36 must pass through 55 said screen.

Said passage 36 terminates in a vertical vent passage 43 formed on one side of the overflow chamber 3 and adapted to be closed by any one of a number of apertured plug members 44 which may be selectively inserted therein to give the desired restriction to inlet of air thereinto. Communicating into the lower end of the overflow chamber 3 is a passage 45 which leads through the 60 casing section 2 to a point beneath the Venturi tube 6 and there communicates with a nozzle 46 which is engaged through the casing section 1 and projects upwardly through the Venturi tube as clearly shown in Figure 5.

As clearly shown in Figures 5 and 6 the lower end of the throttle valve shaft 9 is drilled axially to afford a passage 47 and is drilled transversely with apertures 48, 49 and 50 respectively. Said passage 47 is closed above the transverse aperture 50 by plug 51 and similarly at the end of the shaft is closed by another plug 52. Said throttle valve shaft 9 is also provided with a peripheral groove 53 through which the aperture 48 communicates, and cored within the casing section 2 in register with the grooved and transverse aperture 48 is a priming passage 54 communicating with an inclined priming passage 55 leading into the outlet of the carburetor beyond the throttle valve 8 thereof. This passage 54 65 communicates with an enlarged passage 56 formed in the casing section 2 shown in dotted lines in Figure 4, and leads to and communicates with a vertical passage 57 formed in an extension on one side of the casing section 1 as shown in Figure 6. Also communicating into the lower end of the 70 passage 57 is an idling tube or nozzle 58 which at its lower end connects with a passage formed in a vertical extension 59 on

the float chamber 4 in an extension of the casing section 2 as shown in Figure 3 and is

the float chamber and communicating into fly valve 10 may be opened and closed coincident with rotational adjustment of the valve 60.

57 is a tubular rotatable closure element 60 having an aperture 61 near its lower end adapted to register with a laterally directed air inlet passage 62 formed on the side of the casing section 1 and communicating into the passage 57 through said tubular member 60 when the same is in open position as shown in Figure 6. Threaded into the tubular plug as shown and extending downwardly only sufficient to partially restrict the opening 61 is a stem 63 with a head 64 and the adjustment thereof determines the quantity of fuel withdrawn by suction from the jet 58 and this depends upon the conditions of operation thereof. Attached upon the upper end of the tubular member 63 is a lever 65 shown clearly in Figure 1. Said lever 65 is connected by a link 66 to another lever 67 which is secured upon the upper end of the vertical shaft 11 for the butterfly choker valve 10.

25 The transverse aperture 49 through the throttle valve shaft 9 hereinbefore mentioned and clearly shown in Figures 5 and 6 is adapted to register with an air port 49^a shown directly in rear of said aperture in Figure 5 and provided in the casing section 2 to admit air into the upper portion of the canal or passage 47 within the throttle valve shaft 9 when the throttle is closed.

35 The passage 68 communicates downwardly and into the upper end of the float chamber 4 and when the transverse aperture 50 registers with the passage 68 the interior of the float chamber 4 is opened to the atmosphere so that atmospheric pressure may be 40 realized upon the level therein.

45 As clearly shown in Figures 3 and 6, a drain cock 69 is provided in the lower end of the float chamber 4 whereby the carburetor may be drained when desired. As shown in Figure 4 a screen 70 is provided in the inlet to the standpipe chamber 3 through the inlet fitting 12. As shown in Figures 1 and 4 a passage or canal 71 is cored in the side wall of the casing section 1 and communicates into the outlet from the carburetor beyond the throttle valve and also with a fitting 72. This is provided for attachment of a vacuum fuel supply system and has no relation to the functioning of 55 the carburetor. A throttle lever 73 is attached upon the upper end of the throttle valve shaft 9 and is adjustable thereon so as to permit placing thereof in various positions for idling after attachment of the carburetor to an engine. Also attached upon the upper end of the aforesaid valve element 60 is an operating lever 74 which is 60 adapted to be connected to any type of chamber and rotational adjustment of the choker dash connection on a motor car so tubular valve element 60 shown in Figure 6 that by operation thereof the choker butter-

Operation.

70 The fuel enters the carburetor through the fitting 12, passing through the screen 70 into the overflow chamber 3 and then rises therein until the level reaches a point of overflow into the upright standpipe 17, 75 passing downwardly therethrough around the triangular valve stem 15 into the float chamber 4. As the fuel fills up the float chamber 4 and the overflow chamber 3, the float 21 is elevated and finally upon reaching a predetermined level elevates the pivoted lever 20 sufficiently to raise the stem 15 resting thereon to move the valve closure 14 into closed relation with the passaged seat member 16, through which the entering 80 fuel flows. After the valve closure 14 has closed owing to the rise of level of the fuel in the float chamber 4, the level of the fuel in the overflow chamber 3, when the motor is at rest, is determined by the auxiliary 85 nozzle 46, the discharge end of which is slightly below the upper end of the standpipe 19. The fuel will flow from the overflow chamber 3 through the passage 45 to the nozzle 46 and outwardly therefrom 90 until the level in the overflow chamber is the same as that of the upper end of the auxiliary nozzle 46.

95 Similarly the chamber 22 is supplied through the passage 36 from the overflow chamber 3 by a flow of fuel flowing outwardly therefrom by gravity through the passage 37 and the fixed but adjustable needle valve 40, and the fuel in said chamber 22 and the annular chamber around the tube 30 rises to 100 a level conforming to that in the overflow chamber 3 or at the same level as the discharge end of the nozzle 46. As clearly shown in Figure 5 this level is slightly below that of the apertures 31 in said tube 30. The 105 normal level of the fuel within the tube 30 is that of the fuel in the float chamber 4 so that for the main nozzle of the carburetor there are two levels, that within the annular space around the tube 30 corresponding 110 to the level within the overflow chamber 3, and that within the tube 30 which is the same as that of the fuel in the float chamber 4.

115 Assume first that the carburetor contains 120 fuel and the motor to which the carburetor is attached is about to be started. The throttle valve 8 may be partially opened but the choker valve is entirely closed. Coincident with the closing movement of the choker 125 valve 10, the valve port passages 11^b, 11^c and 11^d are opened to admit air into the float chamber 4 connection on a motor car so tubular valve element 60 shown in Figure 6 that by operation thereof the choker butterfly valve takes place, to close off the air inlet passage 130

62 and as a result, the chamber 57 can only receive inlet thereto from the pipe 59 which communicates with the passage leading to the lower end of the float chamber 4. The outlet from the chamber 57 consists of the passage 56 which leads to the passage 54 and this registers with the grooved periphery 53 of the throttle valve shaft and also communicates through the transverse passage 48 through said shaft with the continuation of the passage 53 and with the inclined passage 55 which enters the outlet end of the carburetor beyond the throttle valve 8.

15 The result of this is a direct passage for raw fuel from the bottom of the float chamber into the outlet of the carburetor. A small amount of air is also admitted through the intermediate port 49 in the throttle valve shaft which communicates with the canal 47 and with an air inlet port in the carburetor casing, but the relative areas of the ports for air and fuel are in favor of the fuel, so that a very rich mixture is supplied into the carburetor for the purpose of starting the motor. Immediately after the motor is started if advisable, the choker valve 10 is fully opened and as a consequence the air inlet to the float chamber 50 is closed and the tubular valve element 60 is rotated into the position shown in Figure 6 so as to open the air inlet 62 into the chamber 57 thus breaking the suction effect to the float chamber through the pipe 59. 55 The extent of opening, however, of the choker valve determines the extent of adjustment of the tubular valve element 60 and consequently determines the draft or suction effect imposed upon the pipe connection 40 59 leading to the fuel in the float chamber. Adjustment of the valve 60 to open position changes the relative areas of air to fuel passages, and enlarges the relative air areas to the fuel areas.

45 When the choker valve 10 is fully opened the valve element 60 is also adjusted into fully open position so as to provide a break in the suction or draft effect in chamber 57 which causes a flow of fuel from the float 50 chamber. The extent of opening afforded by the valve element 60, however, is determined by the adjustment of the stem 63, by its head 64, and this is the adjustment for idling speeds of the engine. That is to say, the fuel withdrawn by suction through the tube 58 depends upon the restriction or suction effect permitted by inlet of air into the chamber 57 according to the adjustment of the stem 63 and the valve 60. A further 55 restriction to the supply of fuel through the tube 58 is the regulated inlet for air into the float chamber by the needle valve 34. The auxiliary nozzle 46 operates to supply fuel as long as a supply of fuel exists in the overflow chamber 3. The overflow chamber is

maintained filled to the upper end of the standpipe because of withdrawal of fuel from the float chamber by the idling tube 58 which lowers the float 32 and admits fuel to the chamber 3, before additional fuel is admitted to the float chamber. Thus for idling speeds of the engine fuel is supplied through the small nozzle 46 and the tube 58.

The fuel, of course, filling the compartment or well 22 surrounding the central tube 30 of the nozzle rises in the annular passage therearound to a point just below the apertures 31, which, for intermediate speeds of operation of the engine permit the fuel to be drawn from the annular passage into the tube and outwardly through the upper end thereof. This fuel supply is normally under the same pressure as the float chamber for the reason that it is at the same level as the fuel in the overflow chamber 3 and the overflow chamber 3 is in communication with the float chamber 4 through the standpipe 17. The adjustment of the needle valve air inlet 34 principally determines the restriction or pressure below atmospheric in the float chamber and consequently, the outlet of fuel from both the overflow chamber and the float chamber.

As reference to Figure 3 will disclose the central tube 30 is provided with apertures 32 above the level of fuel in the float chamber thus permitting an inlet of air into said central tube for passage outwardly at the upper end of the tube when fuel is being withdrawn from the annular space surrounding the tube. Consequently the fuel supplied through the apertures at the upper end of the central tube is met by the stream of air passing through the central tube into the carbureting chamber and this supply of air partially satisfies the demand due to depression and also obstructs by its volume the flow of fuel out of the openings at the nozzle tip. Compensation is therefore provided both by interference at the top of the nozzle and resistance because of the sub-atmospheric condition in the float chamber and is effective upon the fuel in the annular space surrounding the central tube.

For the intermediate speeds of operation 115 of the engine, the adjustment of the carburetor is made by means of the needle valve air inlet 34, the adjustments for idling having been made. Thus fuel is supplied through the small nozzle 46, the tube 58 and the apertures 31 in the tip of the nozzle feeding from the well 22. However, even at intermediate speeds the fuel is not supplied to the well freely under atmospheric pressure even though the throttle valve may have been opened sufficiently to permit entrance of air into the float chamber by way of the throttle valve shaft port 50. This is for the reason that the well 22 receives the fuel from the passage 36 which in turn re- 120 125 130

ceives the fuel from the needle valve controlled passage 37 leading from the overflow chamber 3. If the vent passage 43 for the passage 36 were open, then the fuel would 5 be at atmospheric pressure, but the vent passage is closed by a plug 44, having a small aperture which thereby restricts the pressure in the passage 43, 36 and well 22 when there is a tendency to withdraw fuel rapidly 10 therefrom.

The next consideration is the accelerative and high speed conditions of operation of the engine. A sudden wide opening of the throttle will tend to empty the well 22 and 15 likewise the nozzles 46 and 58 will increase their supply owing to the increased suction, and the opening of the float chamber to atmosphere through the port 50, in the throttle valve shaft to permit atmospheric 20 effects to be realized therein. With the throttle wide open the central tube 30 of the main nozzle supplies fuel directly from the float chamber and with a compensating effect.

As the throttle valve is opened for high speed or heavy load conditions of operation of the engine, fuel is supplied directly from the float chamber through the central tube 30 of the main nozzle. This is readily permitted inasmuch as the float chamber is open 30 to atmospheric pressure through the passage 68 and port 50 and the controlling effect of the air inlet needle valve 34 for the float chamber is negatived. The withdrawal of 35 fuel through the nozzle tube 30 is restricted for compensation by two factors, one the admission of air into the tube above the level of fuel in the float chamber through the apertures 26 and 32 and the other, the 40 size of the aperture 27 in the lower end of the tube 24, which admits fuel to said central tube 30. Thus for wide open throttle conditions of operation the fuel is supplied from the nozzle 46, the tube 58, the annular 45 chamber or well around the main nozzle tube 30 and from the central nozzle tube 30 itself. The regulation in this carburetor for the fuel supplied is effected by a regulation of air admitted to the sources of fuel 50 supply and this offers an ingenious, practical and efficient means of fuel control. The size of the aperture 27, in the tube 24, however, is the main determining factor for supply of fuel to the central tube 20 of the 55 main nozzle for wide open throttle conditions of operation.

I am aware that various details of construction may be varied through a wide range without departing from the principles 60 of this invention and I therefore do not purpose limiting the patent granted otherwise than necessitated by the prior art.

Claims:—

1. A carburetor of the class described

comprising a float chamber, an overflow 65 chamber feeding thereto, means in the overflow chamber controlled from the float chamber to control the inlet of fuel to the overflow chamber, a nozzle in communication with the float chamber, and with the said 70 overflow chamber and having fuel at different levels therein, and an auxiliary nozzle directly connected to the overflow chamber.

2. A carburetor of the class described comprising a float chamber, an overflow 75 chamber at a higher level feeding thereto, means in the overflow chamber controlling the inlet thereto and controlled from the float chamber, a compound nozzle communicating with the float chamber and also with 80 the overflow chamber permitting fuel to be supplied through the tip of the nozzle from the overflow chamber at low speeds of an engine and both from said overflow chamber and float chamber at higher speeds and 85 heavy loads on the engine, and an auxiliary nozzle having direct communication with the overflow chamber and operating to supply fuel during all conditions of operation of the engine at which fuel is supplied from 90 said compound nozzle.

3. A carburetor comprising a compound nozzle, a plurality of fuel supply chambers each separately supplying fuel to said nozzle whereby the fuel stands at different 95 levels in said nozzle and an auxiliary nozzle having direct communication with one of the supply chambers.

4. A carburetor of the class described comprising a compound compensating fuel 100 nozzle, a plurality of sources of fuel supply each supplying fuel separately to said nozzle whereby the levels of fuel in said nozzle are at different heights therein, and an auxiliary nozzle in communication with 105 one of said sources of fuel supply, said auxiliary nozzle adapted to discharge fuel from a level lower than one of the levels in said compound nozzle.

5. A carburetor of the class described 110 comprising fuel supply chambers at different levels, a compound nozzle in the carburetor, communication therewith from each of said fuel supply chambers, whereby the fuel supplied from the respective chambers 115 is contained at different levels therein, and an auxiliary nozzle at a lower level than said compound nozzle and communicating with one of said fuel supply chambers.

6. In a carburetor of the class described 120 comprising a plurality of fuel supply chambers, a plurality of nozzles in the carburetor, a plurality of fuel passages in one of the said nozzles, said passages in communication with said fuel supply chambers whereby 125 fuel in said nozzle has different levels therein corresponding to the levels within the respective fuel supply chambers, passages

providing communication between the respective levels of fuel within the nozzle at a point above the normal level of fuel therein whereby flow of fuel may take place from 5 one into the other and out of the nozzle when a suction draft takes place through the carburetor.

7. A carburetor of the class described comprising a plurality of fuel supply chambers one above the other, an overflow pipe in the upper chamber, a compound compensating nozzle comprising a plurality of passages associated so that the fuel of all of said passages is delivered through the tip 10 of the nozzle and an auxiliary nozzle in communication with one of the fuel supply chambers.

8. A carburetor of the class described comprising a plurality of fuel supply chambers, one of said chambers adapted to supply fuel to the other thereof, a nozzle in the carburetor supplied simultaneously with fuel from both of said chambers and an auxiliary nozzle supplied with fuel from that chamber 20 supplying fuel to the other chamber.

9. A carburetor comprising a carburetor casing, a Venturi tube therein, a float chamber beneath the carburetor casing, a fuel nozzle projecting into the Venturi tube and extending 30 downwardly into the float chamber, a plurality of passages in said nozzle, an overflow fuel chamber communicating with the float chamber, communication between said overflow chamber and certain of the 35 passages in said nozzle, and an auxiliary nozzle projecting through said Venturi tube

and communicating with the overflow chamber.

10. A carburetor of the class described comprising a plurality of fuel supply chambers one higher than the other, an overflow pipe in the upper chamber communicating with the lower, a compound compensating nozzle comprising a plurality of passages associated so that the fuel of all of said passages is delivered through the tip of the nozzle and an auxiliary nozzle at a lower level than the upper end of said overflow pipe and in communication with one of the fuel supply chambers. 40 45

11. A carburetor of the class described comprising a plurality of fuel supply chambers, an overflow pipe in one of said chambers adapted to supply fuel to the other thereof, a nozzle in the carburetor supplied with fuel from both of said chambers, and an auxiliary nozzle at a lower level than said overflow pipe supplied with fuel from that chamber supplying fuel to the other chamber. 50 55

12. A carburetor of the class described comprising a plurality of fuel supply chambers at different levels, a multi-passaged fuel nozzle supplied with fuel independently from both of said chambers and an auxiliary fuel nozzle mounted adjacent thereto and communicating with one of said fuel supply chambers determining the level of fuel therein when the motor is stopped. 60 65

In testimony whereof I have hereunto subscribed my name.

CHARLES L. RAYFIELD.
